UNITED STATES PATENT OFFICE.

CARL SCHEVITZ, OF JACKSONVILLE, FLORIDA.

LAST.

Application filed December 3, 1923. Serial No. 678,299.

To all whom it may concern:

Be it known that I, CARL SCHEVITZ, a citizen of the United States, residing at Jacksonville, in the county of Duval and State of Florida, have invented new and useful Improvements in Lasts, of which the following is a specification.

This invention relates to shoe stretching means, the present invention being an improvement over that forming the subject matter of an application filed by me on Feb. 21, 1921, Serial No. 446,654, issued Feb. 5, 1924, as Patent No. 1,482,584. The principal object of this invention is to provide means for operating the members for actuating the side stretching member simultaneously which includes a hollow screw shaft which is placed over the shaft for operating the instep stretching member.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side view of the device with the cover in section.

Figure 2 is a plan view with parts in section.

Figure 3 is a section on line 3—3 of Figure 1.

Figure 4 is a section on line 4—4 of Figure 2.

The remaining Figures 5 to 10, inclusive, are detail views of the various parts of the improved device.

In these views, 1 indicates the main frame, the side bars of which are provided with the slots 2 and 3 indicates the upright frame which is of channel-shape in cross section and to which the curved side pieces 4 of the main frame are connected. These side pieces are provided with curved slots 5 for receiving the pins 6 of the rocking arms 7 which have their lower ends pivotally connected with the outer members 8 which cooperate with the inner members 9 for moving the side stretching piece 10, which has its shank extending through one of the slots 2. The upper ends of the arms 7 are pivoted to a block 11 which is slidably arranged on the chan-

nel-shaped upright and which has a screw threaded hole 12 for receiving a tubular screw shaft 13 which passes through the top of the upright frame and has its lower end held in a bearing piece 14 which projects from the upright frame. Thus when the tubular shaft is rotated the block will be moved vertically on the upright frame and thus cause the arms 7 to move the outer members 8 for adjusting the said members and the members 9 longitudinally, as described in the before mentioned application. The front ends of the members 8 and 9 are bent at right angles and each member 9 is provided with a projection 9' which is engaged by a part on the member 8 when the same is moved rearwardly for a certain distance so that when this occurs the movement of the member 8 will be communicated to the member 9 and thus both members will be moved rearwardly. The rear ends of the members 9 are connected together by the U-shaped piece 15 and the racks 16 on these members 9 are engaged by the locking plate 17 for holding these members 9 in adjusted position. This locking plate is slidably mounted on the rear of the upright frame and is normally held in lowered position by the spring 18 and is held in raised position by the notched part 19 thereof engaging the small rear part of a slot 20 in the upright frame. The shaft 21 for rocking the bar 22 passes through the tubular shaft and has its threaded part engaging a threaded part of the member 14 so that when the shaft is turned it will be moved longitudinally to rock said bar 22 so as to raise the instep stretching member 23. The longitudinally movable bar 24, which carries the toe stretching member 25, is actuated by the screw shaft 26 which engages a screw threaded socket in the rear end of the bar and which is connected by the gears 27 with the shaft 28 carried by the projections 29 on the rear of the upright frame. This shaft and the shaft 21 have square ends which are engaged by the socket in the member 30 of the handle 31 while the tubular shaft has notches 32 in its upper end which are engaged by the projections 33 on the part 34 of the handle. The heel member 35 has its lower end curved inwardly, as at 36, so as to facilitate the entrance of the device in a shoe. This member is operated in the same manner as described in the before mentioned application though the handle 37 for operating the actuating parts thereof is made round as shown.

The rack bars on the heel member are engaged by the teeth carried by the spring pressed member 41 on the shaft 28 and which is raised out of engagement with the teeth of the rack bars by the means just mentioned.

From the foregoing it will be seen that when the tubular shaft is operated to lower the block the members 8 and 9 at each side of the main frame will be moved forwardly, 10 the movement of the outer member being communicated to the inner members by the shank of the side stretching piece 10 or if this piece is not in position by the bent end of the outer member coming in contact with 15 the bent end of the inner member. When the parts have been adjusted to the proper position the locking plate is moved out of the small part of the notch so that the spring will force it into engagement with the racks 20 on the inner members so as to hold said inner members against movement. Then upon further movement of the block the outer members engaging the beveled ends of the shanks of the side stretching pieces will 25 force said pieces outwardly to stretch the sides of the shoe adjacent the toe. It will of course be understood that either one or two of these side stretching pieces can be used. The drawing only shows one. The in- 30 step member is raised into stretching position by rotating shaft 21 and the toe stretching member is moved by rotating the shaft 28.

The parts not referred to in this application 35 are the same as described and illustrated in the before mentioned patent and it is not thought necessary to describe them in detail in this application. A shield 39 is placed on the top of the upright frame and is held in place by a nut 40 which engages the upper end of the tubular screw shaft. This shield is also provided with perforated arms which are screwed to the top of the upright frame.

It will be seen that I have simplified the 45 construction of my device so that it can be manufactured to sell at low cost and the present device is more simple of operation than the former device.

It is thought from the foregoing description 50 that the advantages and novel features of my invention will be readily apparent.

I desire it to be understood that I may make changes in the construction and in the combination and arrangement of the several 55 parts, provided that such changes fall within the scope of the appended claims.

What I claim is:—

1. A shoe last of the class described comprising a main frame, a side stretching member adapted to be placed at either side thereof, a pair of longitudinally movable members at each side of the main frame, for actuating the side stretching member, an arm

connected with a member of each pair, a block to which the arms are pivoted, a support in which the block is vertically movable, a tubular screw shaft passing through a threaded hole in the block and rotatably mounted in the support, a shaft passing through the screw shaft and having a threaded part engaging a threaded hole in a stationary part of the support, a rocking bar having its rear end engaged by the longitudinally movable shaft, and an instep stretching member carried by the outer end 75 of said rocking bar.

2. A shoe last of the class described comprising a main frame, a side stretching member adapted to be placed at either side thereof, a pair of longitudinally movable members at each side of the main frame for actuating the side stretching member, an arm connected with a member of each pair, a block to which the arms are pivoted, a support in which the block is vertically movable, a tubular screw shaft passing through a threaded hole in the block and rotatably mounted in the support, a shaft passing through the screw shaft and having a threaded part engaging a threaded hole in a stationary part of the support, a rocking bar having its rear end engaged by the longitudinally movable shaft, an instep stretching member carried by the outer end of said 90 rocking bar, a toe stretching member, a longitudinally movable bar carrying the same, a vertically arranged shaft and means actuated thereby for moving the said bar longitudinally.

3. A shoe last of the class described comprising a main frame, a side stretching member adapted to be placed at either side thereof, a pair of longitudinally movable members at each side of the main frame for actuating the side stretching member, an arm connected with a member of each pair, a block to which the arms are pivoted, a support in which the block is vertically movable, a tubular screw shaft passing through a threaded hole in the block and rotatably mounted in the support, a shaft passing through the screw shaft and having a threaded part engaging a threaded hole in a stationary part of the support, a rocking bar having its rear end engaged by the longitudinally movable shaft, an instep stretching member carried by the outer end of said 105 rocking bar, a toe stretching member, a longitudinally movable bar carrying the same, a vertically arranged shaft, means actuated thereby for moving the said bar longitudinally and a crank handle having parts engaging the two vertically arranged shafts and the tubular shaft for rotating the shafts.

In testimony whereof I affix my signature.
CARL SCHEVITZ.
